UNITED STATES PATENT OFFICE

ROBERT W. SILER, OF WILLOWBROOK, CALIFORNIA

PIPE RACKING DEVICE

Application filed September 26, 1930. Serial No. 484,696.

The object of my invention is to provide a rapid and economical means for racking stands of pipe, such as drill pipe, as they are withdrawn from a drilling well.

5 The operation and advantages of my apparatus may best be understood with the reference to the attached drawings and the following description thereof, in which

Fig. 1 is an isometric projection of the complete apparatus,

Fig. 2 is an elevation of the apparatus, looking from left to right of Fig. 1,

Fig. 3 is a detail of the carriage release mechanism shown at 35—36 in Fig. 1, and

15 Fig. 4 is a detail of the clamp indicated at 25 in Fig. 1.

Referring to the drawings, 10 is a stand of pipe (only the lower end thereof being shown) supported above the top of the string

20 11 (as by elevators not shown) and over the rotary table 12. This stand is ready to be placed alongside the stands 13—13 which have already been racked.

A carriage 14 carries six grooved rolls 15—15 which travel on two rails 16—16 horizontally affixed to the frame of the derrick on the side opposite the calf wheel side. This carriage rolls freely on the rails but is drawn toward the right hand end of its travel by a

25 weight 17 suspended from a flexible line 18 running over idlers 19 and attached to the carriage as at 20.

From the carriage a rigid bar or strut 21, which may be reinforced by braces 22, is projected downwardly, carrying at its lower end a yoke 23. In this yoke is swivelled a horizontal bar 24, this bar being so arranged within the yoke that it may swing upwardly a few degrees from horizontal but cannot drop materially below that position. On this bar slides a block 25 which may be locked in any desired position along the length of the bar by a clamp 26.

30 In Fig. 2 the end of the bar 24 and the block 25 and clamp 26 are shown as below the level of the yoke 23, though normally they would be on the same level, as shown in Fig. 1.

35 Clamp 26 is detailed in Fig. 4, in which 24 is the horizontal bar, 25 is the sliding block,

25b is one of a pair of yoke arms extending upwardly from the block, 25c is a pin, 26b is a cam swivelling on the pin, 26c is a hand lever actuating the cam, and 25d is a pad or friction block interposed between the cam face and the upper face of bar 24. A downward movement of hand lever 26c urges the cam against pad 25d and the pad against bar 24, thus locking the clamp and its attached pulley 29 in any desired position along the length of bar 24.

40 A hook 27 is provided, to which is attached a line 28 which passes first over a grooved pulley 29 which revolves on clamp block 25, then over a pulley 30 attached to yoke 23, then over a pulley 31 attached to the strut 21, then over a pulley 32 attached to the left leg of the derrick or other fixed point of support, and is finally given two or three turns around the drum of a power cathead 33, which is kept in constant rotation by any convenient source of power not shown. It would be feasible to omit pulleys 30 and 31 and carry the line from pulley 29 direct to pulley 32. A long free end of line 28b is left beyond the drum, and the line should be of such nature that the drum will revolve freely within the turns until the free end of the line is pulled taut by the hand of the operator.

45 A pin 34 affixed to carriage 14 engages a hook 35 which may be disengaged from the pin by depressing the foot treadle 36, a spring 37 returning the hook into engaging position when the treadle is released.

50 A push-rod 37b has at its lower end a yoke 37c pinned to the inner end of the treadle bar as at 36b and has its upper end pinned to the hook 35, as at 35b, a downward motion of the treadle thus lifting hook 35 free from pin 34 and releasing the carriage 14. The hook should have a sloping face 35c to permit it to ride over pin 34 as the carriage returns.

55 The device is operated in the following manner for racking stands of pipe as each is withdrawn. The hook 35 is latched over the pin 34, holding the carriage in the right hand or retracted position shown in the figures, this being referred to in the claims as the "inner end." The clamp block 25 is fixed in

a desired position on the bar 24 and locked by tightening the clamp. The hook 27 at the end of line 28 is placed about the lower end of the stand, which is swinging free in 5 the elevators. The cathead 33 being in revolution, the bight 28b of the line 28 is pulled taut by the operator, the cathead drum takes in the line, and the lower end of the stand is drawn in the direction of arrow 28 until it 10 rests against the clamp block 25, the upper end of the stand being thereby given a kick sufficient to pass it over the end of the finger. The operator then depresses treadle 36, thus 15 disengaging hook 35 and releasing the carriage which, because of the pull of line 28 over pulley 31 (or 29 as the case may be), moves to the left on the rails 16, the bar 24 carrying the lower end of the stand in a 20 parallel direction, as that indicated by the line and arrow 39, to the position 13a which it is to occupy.

The elevators are then lowered until the stand rests on the floor, the hand line 28b is slackened, allowing line 28 to slip on the cathead drum, the hook 27 is removed from the pipe and the carriage 14 is returned to its original position by the weight 17, the latch 35 riding over hook 34 and locking the carriage in position.

30 Before repeating the above movements with the next stand the clamp block is moved along the bar 24 a distance slightly greater than the outside diameter of the pipe collar or tool joint, so that the next stand will move 35 into a position adjoining that of the first stand.

I claim as my invention:

40 1. A device for racking stands of drill pipe in a derrick, comprising: rails horizontally supported along one side of said derrick; a carriage travelling on said rails; means for drawing said carriage toward the inner end of said rails; an arm projecting from said carriage into said derrick; a winding drum and means for actuating the drum; an idler pulley attached to said arm; an idler pulley supported within said derrick near the outer end of said rails; an idler pulley attached to said carriage; a pipe hook and a line attached thereto, said line being passed over said pulleys and around said drum in such manner that the winding of said line about said drum will draw said hook toward first said idler pulley and will tend to draw said carriage toward the outer end of said rails.

45 2. A device for racking stands of drill pipe in a derrick, comprising: rails horizontally supported along one side of said derrick; a carriage travelling on said rails; a weight and a cord attached to said weight and said carriage and adapted to draw said carriage toward the inner end of said rails; an arm projecting from said carriage into said derrick; a winding drum and means for

actuating the drum; an idler pulley attached to said arm; an idler pulley attached to said derrick near the outer end of said rails; an idler pulley attached to said carriage; a pipe hook and a line attached thereto, said line being passed over said pulleys and around said drum in such manner that the winding of said line about said drum will draw said hook toward first said idler pulley and will tend to draw said carriage toward the outer 75 end of said rails.

3. A device for racking stands of drill pipe in a derrick, comprising: rails horizontally supported along one side of said derrick; a carriage travelling on said rails; means for drawing said carriage toward the inner end of said rails; an arm projecting from said carriage into said derrick; a winding drum and means for actuating the drum; a block movable along the length of said arm, a clamp adapted to affix said block to said arm in any desired position and an idler pulley attached to said block; an idler pulley attached to the derrick near the outer end of said rails; an idler pulley attached to said carriage; a pipe hook and a line attached thereto, said line being passed over said pulleys and around said drum in such manner that the winding of said line over said drum will draw said hook over first said idler pulley and will tend to draw said carriage toward the outer end of said rails.

4. A device for racking pipe stands in a derrick, comprising: rails horizontally supported along one side of said derrick; a carriage travelling on said rails; means for drawing said carriage toward the inner end of said rails; an arm projecting from said carriage into said derrick; a winding drum and means for actuating the drum; an idler pulley attached to said arm; an idler pulley supported within said derrick near the outer end of said rails; a pipe hook and a line attached thereto, said line being passed over said pulleys and around said drum in such manner that the winding of said line about said drum will draw said hook toward first said pulley and will tend to draw said carriage toward second said pulley.

5. A device for racking pipe stands in a derrick, comprising: rails horizontally supported along one side of said derrick; a carriage travelling on said rails; means for drawing said carriage toward the inner end of said rails; means for releasably holding said carriage adjacent the inner end of said rails; an arm projecting from said carriage into said derrick; a winding drum and means for actuating the drum; an idler pulley attached to said arm; an idler pulley supported within said derrick near the outer end of said rails; a pipe hook and a line attached thereto, said line being passed over said pulleys and around said drum in such manner that the winding of said line about said drum will

draw said hook toward first said pulley and will tend to draw said carriage toward second said pulley.

6. A device for racking pipe stands in a derrick, comprising: rails horizontally supported along one side of said derrick; a carriage travelling on said rails; means for drawing said carriage toward the inner end of said rails; a hook attached to said derrick adjacent the inner end of said rails, a pin projecting from said carriage and engaging said hook and treadle means for releasing said hook from said pin; an arm projecting from said carriage into said derrick; a winding drum and means for actuating the drum; an idler pulley attached to said arm; an idler pulley supported within said derrick near the outer end of said rails; a pipe hook and a line attached thereto, said line being passed over said pulleys and around said drum in such manner that the winding of said line about said drum will draw said hook toward first said pulley and will tend to draw said carriage toward second said pulley.

25 In witness that I claim the foregoing I have hereunto subscribed my name this 30th day of August, 1930.

ROBERT W. SILER.
